UNITED STATES PATENT OFFICE

EDWIN S. BROTHERS, OF BROOKLYN, NEW YORK

POWER-DRIVEN TOOTHRUSH

Application filed May 9, 1927. Serial No. 189,802.

This invention is a power driven tooth brush adapted for use in the home. Power brushes for the cleaning of the teeth have heretofore been suggested. They generally 5 embody a suitable flexible shaft provided at the end with a hand piece coaxial of which the power shaft is mounted and the brush is carried directly on the power shaft with the axis of the brush coaxial with the hand piece. 10 In the brushing of teeth, it is important that the bristles of the brush travel in a direction from the gums toward the free edges of the teeth. In order to operate a power brush of the character described so as to brush 15 teeth in this manner, it has heretofore been necessary to provide a prime mover which was reversible, that is to say, a prime mover which would operate the shaft or brush first in one direction to brush certain teeth and then to 20 reverse the operation of the brush in the brushing of other teeth.

With the foregoing considerations in mind, the objects of the present invention may be briefly enumerated as follows. 25 First, to provide a power tooth brush which may be operated in an efficient manner without requiring reversal of rotation of the drive shaft of the brush in the efficient brushing of all the teeth. This is accomplished by 30 mounting the brush at substantially right angles to the handle.

Second, to provide highly efficient and novel means for driving a right angularly disposed brush from a flexible shaft extending 35 through the handle and without necessitating the employment of universal joints, gears or other expensive and disadvantageous mechanical connections.

Third, to provide for the mounting of a 40 brush in a detachable manner upon a flexible shaft in right angular relation to the handle and to permit the brush to be readily mounted and demounted with respect to the handle in order that different members of the family 45 may readily and expeditiously substitute their own individual brushes.

Fourth, to provide an efficient form of 50 brush which may be economically manufactured and which is thoroughly efficient in the performance of its intended functions.

Fifth, to provide driving means for the brush which cannot possibly cause injury to the parts of the mouth, lips, gums, etc.

Sixth, to provide an efficient guard to protect all parts of the structure except the brush 55 from contact with the parts of the mouth.

The foregoing objects and others are accomplished in a structure which will be hereinafter more fully set forth in the following detailed description and in the appended 60 claims.

The accompanying drawing illustrates different practical embodiments of the invention, but the constructions therein shown are to be understood as illustrative, only, and not 65 as defining the limits of the invention.

Figure 1 is a central section of a device embodying the present invention.

Figure 2 is a perspective view showing the brush element of the structure. 70

Figure 3 is a like view illustrating the hub portion of the brush.

Figure 4 is a section on the line 4—4 of Figure 3.

Figure 5 is a central section through the 75 flexible shaft of this invention.

Figure 6 is a side elevation of the structure shown in Figures 1, 7 and 8.

Figure 7 is a view similar to Figure 1, but illustrating a different form of brush and 80 connection with the shaft.

Figure 8 is a front elevation of the structure of Figure 7; and,

Figure 9 is a section on the line 9—9 of Figure 7. 85

Referring to the drawings, 1 designates a handle frame which is shown in the form of a fork or yoke having two arms 2 and 3 and a stem 4. The stem 4 is secured to the conduit 5 by a flexible shaft 6, which extends 90 from any suitable prime mover through conduit 5 to the handle frame 1.

In practically carrying out this invention, it is necessary that the flexible shaft turn a 95 relatively sharp angle at the end of the handle frame. My experience with flexible shafts has been that they are not as a rule capable of operating at sharp angles and I have therefore produced and disclosed in the drawings a flexible shaft which is capable 100

of such operation. The shaft embodies coaxial coil springs 6^a and 6^b, (see Fig. 5), the latter of which extends through the former and is preferably coiled in the opposite direction. In a small tool of the character under consideration, two coaxial springs are found to give very satisfactory results. I find that with such a construction, each spring may be made relatively light, but their aggregate strength will be thoroughly effectual in carrying the load imposed upon the resulting flexible shaft and the shaft will function with far greater efficiency than is possible if a single spring of much heavier weight is employed for this purpose. Furthermore, a shaft embodying concentric springs is much more flexible than a shaft embodying a single spring and heavier weight.

The arm 2 of the handle frame is shown as solid but is provided near its free end and on its inner face with a bayonet slot 7 having an enlarged mouth. The other arm 3 is hollow or tubular and the flexible shaft is adapted to be led through this tubular arm to be connected to a brush positioned between the ends of the arms 2 and 3. In the construction of Figure 1, the flexible shaft projects a short distance beyond the end of the arm 3 and fits into the hub 12 of a brush. This hub is sufficiently long to engage with the bayonet slot 7 which forms a bearing therefor. In the construction of Figure 7, however, the shaft extends from the end of the arm 3 across the space between said arms and finds a bearing in the bayonet slot.

In practice, the novel form of shaft construction shown in Figure 5 may extend the entire distance from the brush through the arm 3 and conduit 5 to the prime mover. This arrangement is shown in Figure 7. I prefer, however, in practice, to extend this specially formed shaft with its coaxial convolutions, so that it will extend only from the brush to substantially the end of the conduit 5, as shown in Figure 1, and the shaft which extends through the conduit is made somewhat heavier and is joined to the shaft 6', formed in accordance with Figure 5, by a sleeve 9.

The brush shown in Figures 1 to 4 is provided, as stated, with a hub 12. This hub is formed at one end with a substantially cylindrical part having therein a squared or polygonal opening into which one end of a flexible shaft 6' is adapted to seat. Said end of the shaft is preferably provided with a suitable tip 8 to which both of the coils 6^a and 6^b are firmly secured, so as to provide for proper driven connection between the hub and the shaft. Beyond the substantially cylindrical portion of the hub, said hub is formed into a substantially hour glass shaped cross section, as shown best in Figure 4, while the free end of the hub is slotted axially, as shown at 19. The bristles 20 of the

brush are wrapped into and firmly gripped by the convolutions of two lengths of wire 21, which are twisted together to grip the bristles after the manner usual in the manufacture of so-called wire back brushes.

After the bristles have been secured to the wire, the wire is bent about the hub 12 after the manner shown in Figure 2, so as to extend along the channeled sides of the hub and rest in said channel in such manner as to secure the parts against rotation. The slot 19 allows the bristle portion of the brush to be moved into a position to expose the free end of the hub in order that said free end may be entered into the bayonet slot 7 which forms a bearing therefor. As stated, the mouth of the bayonet slot is enlarged to permit of the entry of the hub end thereinto, but said hub is provided with circumferential depressions 22 which permit of rotation of the hub in the upper smaller end of the slot and at the same time preclude withdrawal of the hub from the slot.

With this arrangement, it will be apparent that when the end of the hub is disengaged from the slot, a brush and hub assembly may be readily positioned on or removed from the tip 8 of the flexible shaft and when the brush is on the shaft, the end of the hub may be hooked into the slot after the same manner as securing the tongue of a safety pin in position.

This ability to readily remove or replace a brush permits each member of a family to have his own individual brush and to readily associate it with the apparatus when he or she desires to brush his teeth.

I have found that when a twisted wire brush is associated with the hub in the manner desired that the natural resiliency of the wires 20 will cause them to tightly grip the hub so that there will be no tendency of the wires to become disengaged from the hub. It will of course be also understood that in the making of the brush, the bristles are trimmed after the wires 20 have been put over the hub, so as to produce a brush of the desired contour.

The device is provided with a suitable guard 15 in the form of a cowl having segmental ends 16 in which depressions 17 are formed. The ends of the cowl are more or less resilient and permit the depressions to be sprung over trunnions 18 formed on the frame as clearly shown in Figures 1 and 3. By mounting the guard as described, it will be apparent that said guard may be swung from the dotted to the full line position of Figure 6 and vice versa in order to expose either side of the brush for use.

The form of brush which I have shown in Figures 1 to 4 is extremely simple and economical to manufacture, although other forms of brush may be used. For example, Figure 7 to 9, a thoroughly practical, though

more expensive brush is illustrated. Here the shaft is formed so as to extend through the brush to find the bearing in the slot 7. In this form of the invention, that portion of the shaft which extends through the brush is provided with flattened sides and is adapted to extend through a tubular bushing 29, the opposite sides of which are flattened as shown at 10, so that the bushing is locked against rotation with respect to the shaft. The bushing 29 is permanently fixed on the shaft and forms a support for the brush 11. This brush is provided with a hub in the form of a sleeve 12^a, the opposite sides of which are flattened to fit over the bushing 29 and around the outer surfaces of the sleeve the bristles are mounted. These bristles may be secured to the sleeve in any suitable manner. I find it, in practice, convenient to construct the brush 20 in the following manner. Two lengths of wire are twisted together in such manner as to twist into the convolutions suitable bristles. This operation produces a relatively long brush of relatively light weight. This 25 twisted wire, designated 13 in the drawings, with the bristles 14 secured in the convolutions thereof, is then wrapped tightly about the sleeve 12^a with the convolutions of the wrapping relatively close to one another, so 30 as to give a relatively thick brush, i. e., a brush with the bristles fairly close to one another.

At the conclusion of the wrapping operation, the two ends of the twisted wire assembly 13 are permanently secured to the sleeve 12^a and the bristles are thereupon trimmed to form the outer periphery of the brush into a substantially cylindrical contour.

The brush of the character described can 40 be readily positioned on or removed from the bushing 29 by simply disengaging the end of the bushing from the bayonet slot and swinging out the bushing into the dotted line position of Figure 7. After a brush has been 45 positioned upon the bushing, the bushing is swung back into the position in full lines in Figure 7, wherein it is engaged with the bayonet slot which maintains the parts in operative relation. The natural resiliency of the 50 shaft will keep the end of the bushing in the slot 7.

It will be apparent from the foregoing detailed description that the structure is unusually simple, yet it clearly fulfills all requirements for the efficient brushing of teeth. The flexible shaft operates at all times in the same direction and the brush, while mounted directly on the shaft, i. e., without intermediate gearing or universal 60 joint connections, is nevertheless positioned in substantially right angular relation to the axis of the handle. These features are of pronounced novelty in the art to which the invention pertains.

65 In practice, the handle and frame may be

made of metal, celluloid or any other suitable material and the same is true of the guard.

The accompanying drawings show the invention in its preferred practical form, and the invention is to be understood as fully 70 commensurate with the appended claims.

I have particularly referred to the brush as driven by coaxial coil springs. But I wish it understood that the flexible shaft may be of any suitable construction embodying one or more coil springs or otherwise formed so 75 long as it will drive the brush at right angles to the axis of the handle.

Having thus fully described the invention, what I claim as new and desire to secure by 80 Letters Patent is:

1. In a device of the character described, a yoke-like frame, a flexible shaft extending through one arm of the frame and beyond the end of said arm, a hub, one end of which is carried directly by the shaft and the other end of which is journaled in the frame, and a brush mounted on said hub between the arms. 85

2. In a device of the character described, a yoke-like frame, one arm of which is hollow and the other arm of which is provided at its free end with a bayonet slot, a flexible shaft extending through the hollow arm of the frame and beyond the end of said arm, a hub carried at one of its ends by the flexible shaft and detachably engaging with the bayonet slot in the other arm, and a brush embracing the hub between said arms. 90

3. In a device of the character described, a yoke-like frame, one arm of which is hollow and the other arm of which is provided at its free end with a bayonet slot, a hub extending between the arms of the yoke with one end of the hub journaled in the slot, a flexible shaft extending through the hollow arm of the frame and beyond the end of said arm and detachably engaging with the hub to drive the latter, a brush mounted on said hub, a cowl like guard pivotally supported on the yoke and adapted to be swung from one side to the other of the yoke to selectively render opposite sides of the brush operative. 105

4. In a device of the character described, a yoke frame, one arm of which is hollow, a brush positioned cross axially of the axis of said frame and between the arms of the frame, a flexible shaft extending through said hollow arm and into and at least partially through the brush, whereby the flexible shaft forms a support for one end of the brush, and means for journaling the other end of the brush for rotation on the other arm of the frame. 110

5. In a device of the character described, a yoke frame, one arm of which is hollow, a brush positioned between the arms of the frame and extending cross axially of the frame, a flexible shaft extending through the 115 120 125 130

hollow arm of the frame and beyond the end of said arm into and through the brush, and a trunnion secured to the flexible shaft coaxially of the brush and associated with a bearing in the other arm of the frame, whereby the trunnion and flexible shaft support the brush for rotation.

6. In a device of the character described, a yoke frame, one arm of which is hollow, a brush extending cross axially between the 10 arms of the frame and mounted for rotation with respect to the arms of the frame, and a flexible shaft extending through the hollow arm of the frame and beyond the end of said arm into and through the brush to 15 impart rotation to the latter.

7. In a device of the character described, a yoke frame, one arm of which is hollow, a brush extending cross axially between the 20 arms of the frame and mounted for rotation on the arms of the frame, and a flexible shaft extending through the hollow arm of the frame and beyond the end of said arm into and through the brush to impart rotation to the latter, said flexible shaft comprising 25 a plurality of coaxial coil springs with convolutions of adjacent springs coiled in opposite directions to render the shaft flexible and capable of driving the cross axially disposed brush to which it is directly connected.

30 In testimony whereof I have signed the foregoing specification.
